UNITED STATES PATENT OFFICE.

LEMUEL S. MANNING, OF CHICAGO, ILLINOIS.

CAR-PLATFORM.

SPECIFICATION forming part of Letters Patent No. 515,600, dated February 27, 1894.

Application filed July 27, 1893. Serial No. 481,626. (No model.)

To all whom it may concern:

Be it known that I, LEMUEL S. MANNING, of Chicago, in the county of Cook and State of Illinois, have invented a new and useful Improvement in Car-Platforms, of which the following is a full, clear, and exact description.

This invention relates to an improvement in the platforms of railway passenger cars, and has for its object, to provide a self-adjusting extension or apron for the fixed platform of a car, which will bridge the space that intervenes between the ends of two coupled cars, and afford a continuous passage-way from one car to another, thereby conducting to the safety of passengers and employés of the railroad, who have occasion to pass from one car to another while the train is in motion.

To this end my invention consists in the construction and combination of parts, as is hereinafter described and claimed.

Reference is to be had to the accompanying drawings forming a part of this specification, in which similar letters of reference indicate corresponding parts in all the figures.

Figure 1, is a plan view of a detached car platform having the improvement. Fig. 2, is a reverse plan view of the improved platform. Fig. 3, is a longitudinal sectional view, 30 on the line 3—3 in Fig. 2. Fig. 4, is a longitudinal sectional view on the line 4—4 in Fig. 2; and Fig. 5, is a transverse sectional view on the line 5—5 in Fig. 2.

The two side timbers A, provided for the fixed car platform, and shown broken away at their inner ends, are end portions of longitudinal frame timbers of the car for which the platform is provided, said timbers in complete form being extended an equal distance 40 at each end of the car body (not shown), to afford a platform at each end as usual.

The side beams A, are held spaced apart and parallel by the transverse timbers B, which are secured thereto by any preferred means, thus producing a rectangular frame 45 for the reception of the platform floor.

Upon the beams A, a floor C, is imposed and secured, there being a marginal strip a, introduced at each side along the floor edges, 50 and between the beams and floor, so as to pro-

duce similar channels c, which are open along the inner side of the beams, at the side and rear, for the introduction of an apron D; and for the intermediate support of the floor C, a longitudinally extending frame bar A', is secured by its ends to the cross timbers B, as indicated in Figs. 2 and 5.

At a suitable distance from the inner side of each beam A, a tubular spring case E, is secured by its ends to the cross-timbers B, 50 these cylindrical cases having their front ends extended through orifices formed in the front cross-timber at such points as will correctly space the cases apart and disposed in planes parallel with each other and with the side 65 beams A, as shown in Fig. 2.

Preferably there is a radial flange d, formed on or secured to the rear end of each spring case E, which flanges are attached to the face of the rear cross timber B that they impinge 70 upon, the other flanges e, being produced on the front ends of the spring cases that are fastened to the front side of the forward cross timber, so as to retain the cases E, in position on the frame of the fixed platform and adapt 75 them to stiffen said frame as well as to receive other parts of the improvement.

A front buffer block F, is furnished as a support for the flat apron D, that is secured upon the upper surface of the block and projects a proper length rearwardly from the same, the side edges of the apron being preferably convex curved as shown by full and dotted lines in Fig. 1.

Two guide rods G, G', are loosely connected 85 to the buffer block F, and extended therefrom at such points as will permit the rods to slide freely in the spring cases E. The bodies of the guide rods are cylindrical, and for a proper length from their rear ends are reduced in 90 diameter, to permit the loose mounting of the spiral springs I on these diametrically reduced portions, as represented in Figs. 3 and 4, the length of the springs being such as will allow their front ends to bear on the shoulders g, 95 formed on the rods by their reduction, while the rear ends of the springs press upon the rear cross timber B; any preferred means for loosely securing the rear ends of the guide rods in sliding connection with perforations 100

of said timber being provided, washers and cross pins being shown, but a screw nut may be used on each rod if desired.

There is a furcation produced on the front 5 end of each of the guide rods G, G', these forked end portions being made to loosely embrace the buffer block F, on its upper and lower sides.

The front edge of the buffer block F, is in- 10 curved as at h, in Fig. 2, and an anti-friction roller i, is pivoted between the forwardly projecting ends of the forked limbs of the guide rod G, which roller is loosely introduced with- 15 in the space produced by the incurving of the buffer block, the periphery of the roller being in engagement with the incurved wall h. The forked limbs on the front end of the guide rod G', also loosely embrace the upper and lower faces of the buffer block, and are 20 thereto pivoted as shown at m, the forward edges of the limbs mentioned being oppo- 25 sitely and rearwardly sloped from the center line of the pivot and limbs, a proper degree to afford play for the vibration of the buffer block on the pivot bolt m.

There is an abutment plate n, secured to the front of the buffer block F, opposite the limbs of the guide rod G' the sloped edges on the latter loosely pressing upon the plate in service.

30 The apron D, is of such a length as will allow its rear end to enter the space produced by the strips a, between the floor of the fixed platform and the side beams A, and move in it without improper looseness, and to facilitate the lateral rocking vibration of the buffer block F and apron D, the block is cut away in arched form opposite the limbs of the rods, as represented in Fig. 2.

In service, the projection of the buffer block 40 F and apron D, in advance of the fixed plat-

form of a car having the improvement, will adapt the apron to bridge the space between said platform and one on a coupled car that will have its fixed platform impinged by the buffer block at the front edge.

45 The peculiar construction of parts of the improvement permit the apron and buffer block, to accommodate themselves to the side movement of the cars when in transit over the road, so that the apron will be maintained 50 in connection with an adjacent platform on a coupled car while the cars are on a curve, as effectively as if on a straight line, the yielding of the springs I, conducting to such a result.

55 It is evident that when two cars having the improvement are coupled together, the apron D, of each fixed platform will coact to form a continuous platform on straight or curved sections of a railroad over which the cars are 60 drawn.

Having thus described my invention, what I claim as new, and desire to secure by Letters Patent, is—

65 The combination with a fixed car platform, of a buffer block at the front of the platform, a flat apron thereon extending below the floor of the platform, a guide rod forked at its forward end, embracing the buffer block and pivoted thereto, a mating guide rod parallel 70 thereto, an anti-friction roller on said guide rod loosely engaging an incurved front edge of the buffer block, spring cases on the fixed platform loosely engaged by the rods, and springs on the rods and within the cases, sub- 75 stantially as described.

LEMUEL S. MANNING.
